M. RASMUSSEN

TRUNK LOCK

Filed July 7, 1923

Fig. 4.

Fig. 3.

Fig. 2.

UNITED STATES PATENT OFFICE.

MARTIN RASMUSSEN, OF RACINE, WISCONSIN, ASSIGNOR TO HARTMANN TRUNK COMPANY, OF RACINE, WISCONSIN, A CORPORATION OF WISCONSIN.

TRUNK LOCK.

Application filed July 7, 1923. Serial No. 650,187.

To all whom it may concern:

Be it known that I, MARTIN RASMUSSEN, a citizen of the United States, and resident of Racine, in the county of Racine and State 5 of Wisconsin, have invented new and useful Improvements in Trunk Locks, of which the following is a description, reference being had to the accompanying drawings, which are a part of this specification.

10 This invention relates to trunk locks, and has for one of its objects to provide a lock of this character which is particularly adapted for locking together the sections of a wardrobe trunk.

15 A further object of the invention is to provide a lock for wardrobe trunks which will not only securely lock the sections together, but which will clampingly draw the said sections to their fully closed positions.

20 A still further object of the invention is to provide a lock of the character described in which the leverage exerted for the drawing action varies, increasing as the action progresses.

25 A still further object of the invention is to provide a device of the character described which will be simple in construction comparatively inexpensive to manufacture and more efficient in use than those which have been heretofore proposed.

With the above and other objects in view which will appear as the description proceeds, the invention consists in the novel details of construction and combinations of parts more fully hereinafter disclosed and particularly pointed out in the appended 35 claims.

Referring to the accompanying drawings in which like reference characters designate 40 like parts in all the views:

Figure 1 is an elevational view of a wardrobe trunk with the three sections shown in their open positions and provided with a lock constructed in accordance with the present invention;

Fig. 2 is an enlarged elevational view of a portion of the trunk wall, as seen from the inside, illustrating the lock in its open position;

50 Fig. 3 is a view similar to Fig. 2, showing the lock in its closed position; and,

Fig. 4 is an edge elevational view of the parts shown in Fig. 2 as seen from the plane indicated by the line 4—4 of the said figure.

In the said drawings the numeral 5 indicates the wardrobe section of a trunk to which is hingedly connected in the usual manner the drawer section 6. The said wardrobe section, as is usual in this type of trunk, is provided with an open upper end 55 7, which may be closed by the hinged top cover section 8, as is also well known. The drawer section 6 is recessed as at 9 and provided with an escutcheon plate 10, provided with a keeper pin or stud 11, see Figs. 2 and 60 3. If desired, an anti-friction roller 12 may be mounted upon the said stud 11 in order to facilitate the operation of the parts, as will presently appear.

The companion wall of the wardrobe section 5 is likewise recessed, as indicated at 13, to receive the lock assembly 14, which may comprise a casing 15, provided with a pivot pin or stud 16, upon which is oscillatably mounted the locking bolt 17. The said member 17 is preferably shaped substantially as shown in Figs. 2 and 3, taking the form of a portion of a flat disc which is provided with the toe 18 and with a recess 19, which toe and recess are connected by the inclined 70 surface 20, as will be readily understood. The said member 17 is also provided with a substantially radial elongated slot 21, extending through it, which is adapted to receive a pin or stud 22 carried by the lower 75 end of the operating rod 23, which rod is reciprocatingly mounted adjacent the wall of the wardrobe section by suitable straps 24. The said rod extends upwardly beyond the open upper end of the wardrobe section, and terminates in a suitable head 25, which is adapted to be engaged by a disc or plate member 26, carried by the top cover section of the trunk, as will be clear from Fig. 1.

The upper portion of the said rod 23 preferably passes through a substantially cylindrical casing or housing 27, within which is mounted the coiled spring 28, the lower end of which rests against the lower end 29 85 100 of the casing 27, while the upper end of the said spring engages a suitable washer mem-

ber or projection 30, carried by the rod 23. The casing 15 of the lock assembly is also provided with an arcuate slot 31, through which the pin 22 may pass to engage the slot 21 of the oscillating member 17, see Figs. 2 and 3. The said casing is also provided with an inwardly extending wall 32, which is adapted to act as an abutment against which the oscillating member 17

10 may strike to limit its unlocking movement.

The top of the cover member 8 is provided with the usual hasp member 35, which may carry any usual and well known trunk lock 36, adapted to engage with the 15 escutcheon plate 37, carried by the upper wall of the drawer section, as will be clear from Fig. 1.

In operation, assuming the parts to be in the position shown in Fig. 1, if it is desired to close and lock the trunk the drawer section 6 is first moved about its hinges toward the wardrobe section 5, until the two sections almost meet. The top cover section 8 is then swung downwardly on its 25 hinges, thereby bringing the plate or disc 26 into engagement with the head 25 of the rod 23, forcing the same downwardly against the compression of the spring 28.

The downward movement of the said rod 30 23 will, through the pin and slot connection 22 and 21, cause the arcuate movement of the locking member 17 from its position shown in Fig. 2 to that shown in Fig. 3. During this arcuate movement the 35 toe 18 will pass behind the roller 12 carried by the pin or stud 11, and will cause the said roller to be engaged by the inclined surface 20 of the member 17. As the movement is continued this engagement will 40 cause the sections 5 and 6 to be drawn tightly together, until the roller 12 is positioned within the recess 19, as shown in Fig. 3.

During the downward movement of the 45 rod 23, its pin 22 has been caused, by the arcuate slot 31, to move outwardly with respect to the pivot 16 of the locking member 17 from the inner end of the slot 21 to the outer end thereof, as will be readily 50 understood. This downward movement of the pin 22 of course produces an increased leverage upon the member 17 as its movement progresses, which leverage is applied in drawing the two sections intimately together.

When the top cover section has been 55 completely closed, its lock 36 will be engaged with the keeper member of the escutcheon plate 37 in the usual and well known manner.

The unlocking of the trunk is substantially the reverse of the above, the lock 36 being first disengaged from the plate 37, and the top cover section 8 raised to the 60 65 position shown in Fig. 1. This movement

releases the pressure of the plate 26 upon the head 25 of the rod 23, whereupon the spring 28 will urge the said rod 23 upwardly and will produce a reverse movement of the oscillating member 17 to disengage its toe or extension 18 of the keeper roller 12, whereupon the drawer section may be swung open to the position shown in Fig. 1.

While one form of the invention has been 75 illustrated and described it is obvious that those skilled in the art may vary the details of construction as well as the arrangement of parts without departing from the spirit of the invention, and therefore it is not 80 wished to be limited to the above disclosure except as may be required by the accompanying claims.

What is claimed is:

1. In a trunk lock, a keeper member; an 85 oscillatable locking member provided with a recess and a toe adapted to engage said keeper member and draw it into said recess; means movable in one direction by a trunk section for oscillating said locking member; and additional means for moving said last named means in the other direction.

2. In a trunk lock, a keeper member; an 90 oscillatable locking member provided with a recess and a toe adapted to engage said keeper member and draw it into said recess; means comprising a reciprocating rod movable in one direction by a trunk section 95 for oscillating said locking member; and additional resilient means for moving said last named means in the other direction.

3. In a trunk lock, a keeper member; an 100 oscillatable locking member provided with a recess and a toe adapted to engage said keeper member and draw it into said recess, said member being also provided with a substantially radial slot; a reciprocating rod having a pin engaging said slot, said 105 rod being movable in one direction by one of the trunk sections; and a spring associated with said rod for moving it in the other direction.

4. A trunk lock comprising a keeper member; a casing having a guiding slot; a locking member pivotally carried by said casing, provided with a substantially radial slot, a recess, and a toe adapted to engage said keeper and draw it into said recess; a reciprocating rod provided with a pin passing through said guiding slot and into said radial slot, said rod being movable in one direction by a section of the trunk; and a spring associated with said rod for moving it in the other direction.

5. A trunk lock comprising a keeper member; a casing having a guiding slot; a locking member pivotally carried by said casing, provided with a substantially radial slot, a recess, and a toe adapted to engage

said keeper and draw it into said recess; a stop carried by said casing for limiting movement of said locking member in one direction; a reciprocating rod provided

with a pin passing through said guiding slot and into said radial slot, said rod being movable in one direction by a section of

the trunk; and a spring associated with said rod for moving it in the other direction.

10

In testimony whereof I affix my signature.

MARTIN RASMUSSEN.
